CLAIM

The ornamental design for a skateboard for simulating surfing, as shown and described.

DESCRIPTION

FIG. 1 is a perspective view of the invention;
FIG. 2 is a top plan view of the invention;
FIG. 3 is a bottom plan view of the invention;
FIG. 4 is a left side elevation view of the invention, the
right side elevation view being a mirror image thereof;
FIG. 5 is a front elevation view of the invention; and,
FIG. 6 is a rear elevation view of the invention.

FIG 1

FIG 4

FIG 5

FIG 6
